UNITED STATES PATENT OFFICE.

GEORGE E. SHARPE, OF STEUBENVILLE, OHIO.

FIRE-PLACE.

SPECIFICATION forming part of Letters Patent No. 329,224, dated October 27, 1885.

Application filed June 18, 1884. Serial No. 135,348. (No model.)

To all whom it may concern:

Be it known that I, GEORGE E. SHARPE, a citizen of the United States, residing at Steubenville, in the county of Jefferson and State of Ohio, have invented certain new and useful Improvements in Gas and Smoke Consuming Open Fire-Places, of which the following is a specification, reference being made to the accompanying drawings, in which—

10 Figure 1 is a front elevation of my improved gas and smoke consuming open fire-place. Fig. 2 is a vertical section of the same on line xx of Fig. 1. Fig. 3 is a rear perspective view of the improved open fire-place complete. Fig. 4 is a perspective view of the rear shell detached. Fig. 5 is a rear perspective view of the open fire-place with the rear shell removed. Fig. 6 is a vertical section on the line yy of Figs. 2 and 3.

20 The object of my invention is to distribute and retard the gases and smoke arising from the combustion of fuel and to hold them under the action of the fire, so that they will be consumed, and also to mingle with the gases and smoke a supply of hot air in the presence 25 of the fire for the purpose of promoting their combustion.

My invention consists in a novel construction and combination of devices, which may 30 be readily understood from the following particular description, in connection with the accompanying drawings.

Referring to the drawings, the letter A indicates a main shell, which may be made of 35 any suitable refractory material, preferably cast or wrought iron. The rear portion of its top wall is inclined, as shown at a , and extends from the back wall forward to the rear wall, b , of an elevated or dome-like portion 40 of the casing, which has a flue-opening, b' , extending from side to side. The main shell sits upon a hollow base, C , the top wall, c , of which forms a hearth-plate, under which air may pass through openings d in the front 45 wall of the hollow base. Partially embracing the rear portion of the main shell, and permanently attached thereto, is a casing, E , (see Figs. 2 and 5,) having an inclined top wall, e , rear wall, e' , and end walls, $e^2 e^3$, standing at 50 a little distance from the walls of the main

shell, so as to leave an intervening flue-space, which is closed at bottom and in front, but open at top, and communicates with the interior of the main shell by openings f in the walls of the latter. Embracing the entire rear portion of the main shell, and covering the casing E , is a rear shell, G , having a rear wall, g , inclined top wall, g' , extending from the wall g to the rear wall, b , of the dome, (and preferably lapping the ends of the dome, as 60 at $g^2 g^3$) and end walls, as at g^3 . There is a flue-space between the walls of this rear shell and the main shell, and the casing E and the space below the hearth-plate c communicates with this flue-space by means of openings 65 d' in said hearth-plate. (See Figs. 2 and 6.) The under surface of the top wall, a , of the main shell has a lining, H , of fire-brick (or any other suitable refractory material) lying directly over the grate or fire-chamber, and provided with wide downward projections or teeth h , arranged in rows, so that the teeth of each row stand opposite the spaces between teeth of adjacent rows, and thus break up the surface of the lining into obstructed passages, 70 through which the flow of gases and smoke is retarded, and thus subjected for a longer period to the action of the fire than if allowed to pass freely to the opening b' . From the ends of the top lining, H , side linings, I , extend downward, 75 and have their rearwardly and upwardly inclined lower edges resting upon oblique shelves k , which project inwardly beyond said side linings, and have their inner edges bent downward to take over and support the lower 80 side linings, $L L'$, of the fire-chamber, the lower edges of which rest upon shelves $m m'$. These side linings of the fire-chamber stand out from the side walls of the main shell, and are kept at a proper distance therefrom by 85 studs $n n'$, projecting from said walls. The rear edges of the side linings join with a back lining, L' , which rests upon a rear shelf, m' , and stands at a proper distance from the rear wall, a' , of the main shell to leave a flue space. 90 Its rear surface abuts against studs $n' n'$, projecting from the shell, and its upper edge reaches snugly up to a rear horizontal shelf, k' , which joins with the oblique side shelves, $k k'$. At the tops of both the side linings and 95

100

back linings of the fire-chamber are openings *l*, forming communicating passages between the top of the fire-chamber and the flue-spaces behind the linings. In the shelves *m m* and 5 *m'*, which support the fire-chamber linings, are openings *q*, allowing communication between the space under the fire-chamber and the spaces behind the linings. A short distance above the fire-chamber is a flatwise horizontal deflecting-plate, *P*, the ends of which rest upon suitable ledges projecting from the upper side linings, *I I*. The purpose of this 10 plate is to deflect the products of combustion in a direction to strike the top lining, *H*, so that the smoke and gases will be distributed and retarded so as to be subjected to the heat of the fire-chamber and consumed instead of passing directly upward and off to the chimney through the opening *b'*. The grate-bottom 15 *R*, basket *S*, and ash-pit screen *T* may be of any suitable or well-known construction and supported in any desired manner, and as they form no part of my improvement they need not be particularly described.

20 25 The operation of my improved smoke and gas consuming open fire-place is as follows: When a fire has been started in the fire-chamber, the products of combustion which arise therefrom—that is, the smoke and gases—are deflected by the plate *P* in the direction of the arrow No. 1, and pass among the teeth *h* toward the opening *b'*. A draft is thus started, which causes cold air to enter through the openings *d* and to pass under the hearth-plate *c* in the direction of the arrows No. 2, 30 and thence up through the openings *d'* and between the casing *E* and the rear shell. At the top of the casing *E* it turns and passes downward between said casing and the main shell to the openings *f*, where it divides, a portion going downward through the openings *q* to the ash pit or space under the fire-chamber, and the other portion rising and passing 35 through the openings *l* into the top of the fire-chamber. In its passage through these flues the air becomes heated, and joining with the gases escaping from the fire promotes their combustion. The air will only pass down under the fire-chamber in the direction of 40 arrows No. 3 when the usual register in the ash-pit screen is closed, which will usually be done after the fire is well started. I have found in practice that by causing the heated air to be mingled with the smoke and gases rising from 45 the fuel and retarding and dispersing these gases, smoke, and hot air by means of the teeth *h* the gases and smoke are very efficiently consumed.

I am aware that a cooking-stove has had the direct back wall of its fire-chamber provided 60 with teeth to hold the fuel off from the wall-plate and protect said plate from rapid burning away, and I lay no claim to a stove so constructed. The overhanging toothed lining in my fire-place has quite a different function 65 from the said toothed back wall, in that the teeth of my lining intercept and retard the gases and smoke after they have escaped from the fuel-bed and promote their combustion in the form of flame.

Having now described my invention and explained its operation, what I claim is—

1. The combination, with the main shell provided with a fire-chamber and elevated hearth-plate having openings to admit air beneath, of the rear shell and the intermediate casing, *E*, open at top and closed at bottom, suitable openings being provided to permit air to rise from below the hearth-plate into the space between the main and rear shells and to 80 pass from between the intermediate casing and main shell to the fire-chamber, substantially as described.

2. The combination, with the main shell, its fire-chamber, and oblique top lining provided 85 with flat teeth *h*, arranged in tortuous or zig-zag rows, of the deflecting-plate *P*, projecting from the front rearwardly toward the lower edge of said lining, as set forth.

3. The combination of the main shell having 90 the oblique shelves *h* and rear straight shelf, *k*, and provided with openings *f*, the fire-chamber linings arranged below said shelves, and having openings at top, the rear shell and intermediate casing, and the elevated hearth-plate with openings for access of air beneath 95 it, and provided with openings to admit air to the space between the main and rear shells, substantially as described.

4. The combination, with the main shell 100 mounted on the elevated hearth-plate, its fire-chamber, and oblique top lining provided with flat teeth *h*, arranged in tortuous or zigzag rows, of the deflecting-plate *P*, projecting from the front rearwardly toward the lower edge of 105 said lining, and the rear shell and intermediate casing constructed, as described, with intervening spaces connected with the space under the hearth-plate and with the fire-chamber, substantially as set forth.

GEORGE E. SHARPE.
